Samuel W. Gibbs, of Albany, N. Y.

Assign to

A. H. McC. Arthur & C. of Hudson, N. Y.

Letters Patent No. 718 - Dated August 14th 1855.

The schedule referred to in these Letters Patent and making part of the same

Be it known that I, Samuel W. Gibbs of the City of Albany, State of New York, have produced a new and original ornamental design for the plates of a stove, and I hereby declare that the annexed drawings, forming part of this specification, are full, and accurate delineations of the said plates, with their ornamental parts, the side plate not represented being symmetrically similar to the one shown.

The Stove to which the plates belong is called the Reliance Cooking Stove

Figure 1. represents the front plate with its doors.

Figure 2. represents the side plate with its doors.

Figure 3. represents the hearth plate drawn a little foreshortened to show its front edge to advantage.

What I claim as my production and desire to secure by Letters Patent is the combination and arrangement of ornamental figures, and forms represented in the accompanying drawings forming together the Ornamental Designs for the plates of a Stove,
